Patented Mar. 19, 1918.

FIG. 2.

Inventor

By

Ernest Maker:
W. H. Tracy, Attorneys.

UNITED STATES PATENT OFFICE.

ERNEST MAKER, OF SANTA ROSA, CALIFORNIA.

PUNCHING DEVICE.

1,260,226.

Specification of Letters Patent. Patented Mar. 19, 1918.

Application filed June 12, 1917. Serial No. 174,328.

To all whom it may concern:

Be it known that I, ERNEST MAKER, a citizen of the United States, residing at Santa Rosa, in the county of Sonoma and State 5 of California, have invented certain new and useful Improvements in Punching Devices, of which the following is a specification.

This invention relates to improvements in 10 devices for simultaneously producing a discharge aperture and a vent aperture in cans or like receptacles containing liquids, to enable the contents of the can to be discharged through one of the orifices or apertures and to admit air through the other aperture to prevent the formation of a vacuum within the receptacle which would otherwise prevent the free discharge of the contents.

20 Another object of the invention is to provide a simply constructed device of this character wherein provision is made for adjusting the puncturing devices toward and away from each other to adapt the device to 25 cans of varying sizes.

Another object of the invention is to provide a device of this character including puncturing devices movable toward and away from each other, and means whereby 30 the puncturing devices may be detached for sharpening or replacing broken or impaired portions.

With these and other objects in view, the invention consists in certain novel features 35 of construction, as hereinafter shown and described and then specifically pointed out in the claim; and in the drawings illustrative of the preferred embodiment of the invention:

40 Figure 1 is a perspective view of the improved device;

Fig. 2 is a detached perspective view of one of the puncturing devices;

Fig. 3 is an enlarged section on the line 45 3—3 of Fig. 1.

The improved device comprises a frame including a lower member 10 for carrying the puncturing devices, and members 11 rising from the terminals of the lower member 10, and an upper member 12 which likewise constitutes a hand grip to enable the implement to be operated, the upper part of the member 12 is curved upwardly and the upwardly curving portion turned over as shown

at 13 to increase the grip and likewise reinforce and stiffen the frame. The lower member 10 of the frame is provided with a longitudinally directed guide slot 14.

Slidably disposed upon the member 10 of the frame are coacting punching devices, 55 precisely alike and interchangeable. Each punching device comprises a body or head portion 15 pointed at one end as shown at 16, and forked or bifurcated at the upper portion to form a seat represented at 17, to 60 receive the portion 10 of the frame, as shown in Fig. 1. The seat 17 corresponds in depth to the width of the member 10 including its slot 14, so that the upper end of the body is even with the upper line of the member 10. 70 Inserted through each of the forked portions of the members 15 is a combined dividing and holding bar or pin 18, the latter bearing against the upper and lower sides of the slot 15, the pins and the slot coacting to 75 retain the punch devices in parallel relation to the frame. By this means the bodies 15 are secured in position upon the portion 10 of the frame, while at the same time they are free to be moved longitudinally of 80 the latter to enable the points 16 to be adjusted near to or farther from each other. The punching members may thus be readily attached to and detached from the frame by removing the pins 18, so that if the points 85 become dulled or otherwise impaired they can be sharpened or renewed without discarding the remainder of the device.

By forming the frame with the member 10 of considerable length the improved implement may be readily adapted to cans of 90 varying sizes.

In operating the improved device one of the points 16 is disposed in position upon the can where it is desired to form a discharge opening or orifice, and the other point 16 disposed as remotely as possible from the other point to serve as a vent, or to permit the entrance of air to facilitate the discharge of the contents of the can. 95

The improved implement may likewise be employed for forming any required number of the apertures as will be obvious.

The improved implement is simple in construction, can be inexpensively manufactured and of any suitable material and of any suitable strength. 105

The supporting frame will preferably be

stamped from a single sheet of metal of any required size and the strengthening rib bent over, as shown.

Having thus described the invention, what is claimed as new is:

An implement of the class described comprising a supporting frame including an upper hand grip member and a lower member divided by a longitudinally directed slot 10 into inner and outer parts, coacting punch-

ing and puncturing devices each including a puncturing point and a bifurcated portion forming a seat to receive both parts of the slotted member, and pins extending respectively through the bifurcated portions and 15 through the slot, whereby the puncturing devices are slidably coupled to the frame.

In testimony whereof I affix my signature.

ERNEST MAKER. [L.S.]
